UNITED STATES PATENT OFFICE.

JOHN H. HUNT, OF DAYTON, OHIO, ASSIGNEE, BY MESNE ASSIGNMENTS, TO DELCO-LIGHT COMPANY, OF DAYTON, OHIO, A CORPORATION OF DELAWARE.

IGNITION SYSTEM.

Application filed July 14, 1919. Serial No. 310,646.

To all whom it may concern:

Be it known that I, JOHN H. HUNT, a citizen of the United States of America, residing at Dayton, county of Montgomery, State 5 of Ohio, have invented certain new and useful Improvements in Ignition Systems, of which the following is a full, clear, and exact description.

This invention relates to ignition systems 10 for internal-combustion engines, and has among its objects the provision of ignition by utilizing a source of current at relatively high voltage.

In carrying out this object of this invention I provide in combination with a source 15 of current at relatively high voltage, an ignition timer for periodically making and breaking the ignition circuit, and an ignition coil which is constructed and arranged 20 so that a spark will be obtained at the instant of make of the circuit. I provide also means for eliminating the effect of the spark at the instant of break in a manner such as to prevent undue arcing at the timer 25 contacts.

Other and further objects and advantages 30 of the present invention will be apparent from the following description, reference being had to the accompanying drawings, wherein a preferred embodiment of the present invention is clearly shown.

In the drawings:

Fig. 1 is a sectional view of a timer and distributor unit, together with a wiring diagram illustrating one embodiment of the invention;

Fig. 2 is a plan view of the unit with the distributor head removed;

Fig. 3 is a sectional view of the timer, 40 taken on the line 3-3 of Fig. 1;

Fig. 4 is a view similar to Fig. 1 showing a modified form of the invention, the sectional view of the distributing device shown in Fig. 4 being taken on the line 4-4 of 45 Fig. 5;

Fig. 5 is a bottom plan view of the ignition distributor head shown in Fig. 4; and

Fig. 6 is a diagrammatic perspective view 50 of the timing and distributing apparatus, certain parts being shown in section, together with a wiring diagram illustrating a

still further embodiment of the invention.

In the drawings, a timer cup 20 is supported upon a base 21 which is adapted to be supported in order that the timer cam shaft 55 22 may be driven by the engine through gearing (not shown). Shaft 22 carries timer cam 23 and distributor rotor 24. Cam 23 cooperates with breaker lever 25 pivotally mounted at 26 upon the timer cup 20, 60 but insulated therefrom. Lever 25 carries contact 27 normally held in engagement with contact 28 by means of spring 29. Contact 28 is carried by a bracket 30 which is mounted upon the timer cup 20, but insulated therefrom.

Timer cup 20 supports a ledge 31 upon which is mounted a ring 32 of insulating material which is provided with inserts 33 of conducting material, each of which is 70 electrically connected with the timer cup through the ledge 31 and thereby grounded upon the engine frame as indicated by the ground connection 34. Distributor rotor 24 is provided with a brush 35 which is arranged to contact with the inserts 33. Brush 35 is connected by means of a conductor 36 contained within the rotor 24 with a conducting strip 37 which extends from the center of the upper surface of said rotor to 75 the brush 38.

Timer cup 20 supports distributor head 40, which includes a distributor track 41 provided with a plurality of stationary distributor contacts 42 with which the brush 85 38 is arranged to contact. These contacts 42 are indicated by dot and dash circles in Fig. 2 in order to show their relation with the inserts 33. Distributor head 40 is provided with a center contact 43 arranged to engage 80 the conducting strip 37.

An ignition coil 50 is provided with continuous core 51 which provides a closed magnetic circuit. The primary winding 52 is connected by wire 53 with stationary contact 28, and by wire 54 with a controlling rheostat 55. Rheostat 55 is connected by wires 56 with a high voltage battery 57 or other high voltage source of current. Battery 57 is connected by wire 58 with the 100 breaker lever 25. A condenser 59 is connected in parallel with the timer contacts 27

and 28. The secondary winding 60 of coil 50 is grounded at 61 and connected by wire 62 with the central distributor contact 43. The stationary contacts 42 are each connected with an engine spark plug, one of which is indicated at 63.

The operation of the invention is as follows: As stated above, the coil is provided with a closed magnetic circuit, and the ratio 10 of transformation and inductance of the coil is such that a spark will be provided at the instant of make of the primary circuit. Fig. 3 shows the timer contacts at the instant of engagement, the direction of rotation of the 15 cam being clockwise as viewed in Figs. 2 and 3. It will be noted that at the same instant the distributing brush 38 will be in contact with one of the distributor contacts 42, to distribute the sparking impulse induced in winding 60 at the instant of make to one of the spark plugs 63. Before the primary circuit is broken by the separation 20 of contacts 27 and 28, brush 35 will have come into engagement with one of the inserts 25 33, and will still be in engagement with said insert 33 at the instant of separation of contacts 27 and 28. The sparking impulse, which is induced at the instant of break of the primary circuit in the secondary winding 60, is diverted from the spark plug 63 and passes directly from contact 43 through conductor 36, brush 35, insert 33, timer cup 20, to ground connection 34.

By reason of the particular construction 35 of the coil referred to, these provisions for short-circuiting or diverting the sparking impulse away from the spark plug, also provide for the reduction of the inductance of the coil to a low value at the instant of 40 break of the primary circuit. This may be attributed to the low resistance of the short-circuited secondary circuit, which permits a rush of current through the secondary circuit at the instant that the timer contacts 45 begin to open. This current sets up a strong magnetic field in the coil 50 in the direction of the existing field and tends to maintain its strength unchanged until the timer contacts are completely opened and the primary circuit is broken. The result is that 50 when the primary circuit is broken upon the separation of contacts 27 and 28, the induced current which would otherwise be present is effectively suppressed and sparking 55 ing at said contacts will not be excessive.

After the contacts 27 and 28 have been opened, and while still separated from one another, the brush 35 will have moved out of engagement with the inserts 33, so that 60 when the primary circuit is again made by the closing of the contacts 27 and 28, the short-circuiting device will be rendered ineffective.

From the foregoing description it is apparent that a double protection is provided

against the possibility of obtaining a spark at the instant of break of the primary circuit. In the first place the distributor brush 38 will be so far separated from the distributor contacts 42 that there will be very 70 little possibility of a spark jumping along the distributor track. In addition to this, any sparking impulse which would tend to jump across this gap between brush 38 and one of the contacts 42, will be short-circuited 75 by the short-circuiting brush 35 and the connections therewith which have been described. It will be understood also that this short-circuiting device has a double function, namely, to prevent sparking at a 80 spark plug at the instant of break of the primary circuit, and to reduce arcing at the timer contacts, so that metals which are ordinarily used as contacts in ignition systems operating at low voltage can be used 85 as well in ignition systems operating at high voltage.

Figs. 4 and 5 illustrate a second form of the invention. This form differs from the form described in the foregoing in the following particulars: The timer cup 20 and the base 21 form a ground contact for the breaker lever 25 and the movable timer contact 27, and the condenser 59 is provided with a ground contact 59^a. The elements 90 31 and 32 are omitted, and the cam shaft 22 supports a rotor 24^a which carries only the conducting strip 37 and the brush contact 38. The distributor head 40^a differs from the distributor head 40 described in the first form of the invention, in that, in addition to the regular distributor contacts 42, this distributor head 40^a carries a plurality 95 of grounding contacts 70, each provided with conducting strips 71 which terminate 100 flush with the lower edge of the distributor head 40^a, as shown in Fig. 4. These grounding contacts 70 perform the same function as the inserts 33 shown in Fig. 2. This form 105 of the invention is preferable where it is desired to use the conventional type of distributor rotor. The grounding contacts are built into the distributor head in such a manner that when the distributor head is mounted upon the timer cup, these grounding contacts will all be connected with a common ground.

The operation of this form of the invention is precisely the same as that of the form 110 previously described. At the instant of make of the primary brush circuit, the contact 38 will be opposite one of the stationary distributor contacts 42, but at the instant of break of the primary circuit the brush contact 38 will be in engagement 115 with one of the grounding contacts 70. In this manner a discharge path for the ignition coil is provided, so that its energy may be discharged at the time of break of the ignition circuit without undue arcing of the 120 125 130

timer contacts or injury to the ignition coil.

A still further form of the invention is illustrated in Fig. 6. In this form of the invention the timer is exactly the same as the timer shown in Fig. 1. The timer cup, however, has been omitted for the sake of clearness. The cam shaft 22 carries a conventional type distributor rotor 24^a provided with conducting strip 37 and brush contact 38 shown in Fig. 4 as well as Fig. 6. The distributor head 40, shown in Fig. 6, is provided with stationary segmental contacts 80 which are engaged by the rotor brush contact 38. The arrangement of these contacts 80, the rotor brush contact 38, and the cam 23 is such that at the instant of engagement of contacts 27 and 28, the rotor brush contact 38 will be in engagement with one of the contacts 80 to distribute the sparking impulse, created at the time of make, to the proper spark plug of the engine. At the time of separation of contacts 27 and 28 the rotor brush contact 38 will still be in engagement with the same contact 80. Thus it will be seen that a discharge path is provided for the ignition coil at one of the spark plugs 63. The explosive mixture in the engine having been ignited, sparking at the spark plug at the time of break of the ignition circuit will do no harm, if the effect produced by permitting a discharge of the ignition coil at one of the spark plugs at the time of break of the ignition circuit, is substantially the same as where the discharge path for the ignition coil at the time of break includes a short-circuit around the spark plugs, as in the case of the forms of the invention hereinbefore described.

While the forms of mechanisms herein shown and described constitute preferred embodiments of the one form of invention, it is to be understood that other forms might be adopted and various changes and alterations made in the shape, size, and proportion of the elements therein without departing from the spirit and scope of the invention.

What I claim is as follows:—

1. In an ignition system, the combination with an engine having ignition means; of a current source at relatively high voltage; a timer for providing an intermittent flow of current from said source in said system and an ignition device having means for preventing the flow of current to the ignition means at the instant of interruption of current.

2. In an ignition system, the combination with an engine having ignition means; of a current source at relatively high voltage; a timer including cooperating contacts for providing an intermittent flow of current from said source in said system and an ignition device having means for preventing the flow of current to the ignition means at the

instant of interruption of current, and for preventing excessive arcing at the timer contacts.

3. In an ignition system, the combination with an engine having a spark plug; of a current source at relatively high voltage; of an ignition timer having cooperating contacts; an ignition coil connected with said current source and timer and arranged to provide sparking at the plug at the instant of make; and means for providing a short-circuit around the plug at the time of break of said timer.

4. In an ignition system, the combination with an engine having a spark plug; of a current source at relatively high voltage; of an ignition timer having cooperating contacts; an ignition coil connected with said current source and timer and arranged to provide sparking at the plug at the instant of make; and means for providing a short-circuit around the plug at the time of break of said timer, and cooperating with said coil to prevent undue arcing at the timer contacts.

5. In an ignition system, the combination with an engine having a spark plug; of a current source at relatively high voltage; of an ignition timer having cooperating contacts; an ignition coil having a closed magnetic circuit connected with said current source and timer and arranged to provide sparking at the plug at the instant of make; and means for providing a short-circuit around the plug at the time of break of said timer.

6. In an ignition system, the combination with an engine having a spark plug; of a current source at relatively high voltage; of an ignition timer having cooperating contacts; an ignition coil having a closed magnetic circuit connected with said current source and timer and arranged to provide sparking at the plug at the instant of make; and means for providing a short-circuit around the plug at the time of break of said timer, and for short-circuiting the ignition coil secondary winding at the time of break of said timer in order to prevent undue arcing at the timer contacts.

7. In an ignition system, the combination with an engine; of a current source at relatively high voltage; a timer including cooperating contacts for providing an intermittent flow of current from said source in said system; and ignition devices arranged to provide ignition at the instant of flow of current while preventing excessive arcing at the timer contacts at the instant of interruption of current.

8. In an ignition system, the combination with an engine; of a current source at relatively high voltage; a timer including cooperating contacts for providing an intermittent flow of current from said source

in said system; an ignition coil connected with said timer and said source and arranged to provide ignition at the instant of flow of current; and means adapted to 5 come into operation before the interruption of said current flow whereby to prevent excessive arcing at the contacts.

9. In an ignition system, the combination with an engine: of a current source at relatively high voltage; a timer including cooperating contacts for providing an intermittent flow of current from said source in said system; an ignition coil having a closed magnetic circuit, a primary winding 15 connected with said current source and said timer and a secondary winding arranged to be connected with a spark plug of the engine, said coil being arranged to provide ignition at the instant of current flow in 20 said primary winding; and means for short-circuiting the secondary winding before the instant of interruption of primary current whereby to prevent excessive arcing at the timer contacts.

25 10. In an ignition system, the combination with a multi-cylinder engine having spark plugs; of a current source at relatively high voltage; an ignition coil arranged to provide sparking impulses at the 30 instant of flow of current therethrough from said source; and engine operated means for providing an intermittent flow of said current through said coil, for distributing said impulses to the spark plugs and having provisions for preventing ignition at the instant 35 of interruption of current flow.

11. In an ignition system, the combination with a multi-cylinder engine having spark plugs; of a current source at relatively high voltage; an ignition coil arranged to provide sparking impulses at the instant of flow of current therethrough from said source; and engine operated means for timing the flow of current 40 through said coil, for distributing said impulses to the spark plugs, and having provisions for preventing excessive arcing at the contacts.

50 12. In an ignition system, the combination with a multi-cylinder engine having spark plugs; of a current source at relatively high voltage; an ignition coil arranged to provide sparking impulses at the instant of flow of current therethrough 55 from said source; and engine operated means for timing the flow of current through said coil, for distributing said impulses to the spark plugs, and having provisions for preventing ignition at the instant 60 of interruption of current flow and for preventing excessive arcing at the contacts.

65 13. In an ignition system, the combination with a multi-cylinder engine having spark plugs; of a current source at rela-

tively high voltage; an ignition coil arranged to provide sparking impulses at the instant of flow of current therethrough from said source; and engine operated means including cooperating timer contacts 70 controlled so as to provide an intermittent flow of current through said coil, and including a distributor of said sparking impulses, the said means being arranged so that when the current from said source is interrupted, the distributor is inoperative. 75

14. In an ignition system, the combination with a multi-cylinder engine having spark plugs; of a current source at relatively high voltage; an ignition coil arranged to provide sparking impulses at the instant of flow of current therethrough from said source; and engine operated means including cooperating timer contacts 80 controlled so as to provide an intermittent flow of current through said coil, and including a distributor of said sparking impulses, the said means being arranged so that when the current from said source is interrupted, the distributor is inoperative, 85 and the ignition coil is short-circuited. 90

15. In an ignition system, the combination with a multi-cylinder engine having spark plugs; of a current source at relatively high voltage; an ignition coil arranged to provide sparking impulses at the instant of flow of current therethrough from said source; and engine operated means including cooperating timer contacts controlled 95 so as to provide an intermittent flow of current through said coil, including a distributor for distributing sparking impulses to the spark plugs, and including provisions for short-circuiting the ignition coil at the instant of interruption of said current. 100

16. In an ignition system, the combination with a multi-cylinder engine having spark plugs; of a current source at relatively high voltage; an ignition coil arranged to provide sparking impulses at the instant of flow of current therethrough from said source; and engine operated means for controlling in recurrent sequence the closing of the primary ignition circuit, the short-circuiting of the secondary ignition circuit, 110 the opening of the primary ignition circuit, 115 and then the interruption of said secondary short-circuit. 120

17. In an ignition system, the combination with a multi-cylinder engine having spark plugs; of a current source at relatively high voltage; an ignition coil arranged to provide sparking impulses at the instant of flow of current therethrough from said source; and engine operated means for controlling in recurrent sequence the closing of the primary ignition circuit, the short-circuiting of the secondary ignition circuit, 125 the opening of the primary ignition circuit, 130 and then the interruption of said secondary

short-circuit, said means including provisions for distributing sparking impulses at the instant of closing of said primary circuit, said distributing provisions being operative when said primary circuit is interrupted.

18. In an ignition system, the combination with an engine having a spark plug; of a current source at relatively high voltage; an ignition timer having make and break contacts; an ignition coil connected with said current source and timer and arranged to provide sparking at the plug at the instant of make; and means providing a discharge path for said coil at the instant of break of said timer.

19. In an ignition system, the combination with an engine; of a current source at relatively high voltage; a timer having operating contact for providing an intermittent flow of current from said source in

said system; and ignition devices arranged to provide ignition at the instant of flow of current and having provisions for preventing undue arcing of the timer contacts at the instant of interruption of current.

20. In an ignition system, the combination with an engine having ignition means; of a current source of relatively high voltage; a timer for providing an intermittent flow of current from said source in said system; and an ignition device connected with said current source and said timer and having means for conducting current to the ignition means at the instant of flow of current.

In testimony whereof I affix my signature.

JOHN H. HUNT.
